STRUCTURAL ELEMENT

Melville K. Weill and Etienne Mautner, New York, N. Y., assignors to Skydyne Inc., New York, N. Y., a corporation of New York

Application April 29, 1940, Serial No. 332,194

7 Claims. (CL. 20—91)

This invention relates to structural elements useful generally in the arts where strength, rigidity and lightness are desirable and more particularly in the art of airplane construction.

In the accompanying drawings: Fig. 1 is a sectional view of one form of the invention. Figs. 2, 3, 3A and 4 are views of other forms, also shown in section. Fig. 5 is a flatwise view of the structure shown in Fig. 4 with part of one layer of the surface material removed and partly in section on the line 5—5 of Fig. 4. Fig. 6 is a sectional view of one form of a pin or post. Fig. 7 is an alternative structure shown in section. Fig. 8 is a sectional view taken on line 8—8 of Fig. 7, shown with one surface layer removed. Fig. 9 is a sectional view of a structure like that of Fig. 7 except that it is bent to show the form taken at the forward edge of an airplane wing. Fig. 10 is a view of another alternative structure, also in section. Figs. 11 and 11A are views of other alternative structures, also in section. Fig. 12 is a flatwise view of the structure of Fig. 11, shown with one surface layer removed. Fig. 13 is a perspective view partly in section and partly fragmentary to show the manner in which a structure like that of Figs. 4 and 5, for example, may be formed into a wing for an airplane. And Fig. 14 is an enlarged view, in section, of the preceding edge of the wing structure.

In the drawings the character 1 represents a 30 layer or block of light weight material, which may be of pulverized or granular cork held in mass by a suitable binder such as glue, and 2 is a wire mesh screen imbedded therein for strengthening the layer laterally. On either side of this cork-screen combination there may be placed for stiffening purposes (Fig. 2, etc.) surface layers of plywood 3. In Figs. 1 and 2 the layer of cork is thin, being of just sufficient thickness to cover the screen in order to provide cushion against abrasive action or cutting of the wire mesh into the surface of an adjacent layer. In Fig. 3 the cork layer is thick enough to lend additional strength to bending forces to which the structure may be subjected. In Fig. 3A two wire mesh screens are imbedded in the cork layer, each as close as is practical to the surface thereof which still further increases the strength of the structure over that shown in Fig. 3 and with only a minimum increase in weight.

As shown in Fig. 4 the cork layer is of such shape that open spaces or grooves 4 are provided to reduce the bulk of the material and therefore to lessen its total weight, without substantially reducing its strength. The resistance of this ele-

ment to crushing forces is enhanced by posts 5, which may be wood pins or take other forms such as that of a metal tube 6 (Fig. 6) flared at either or both ends. The ends of such posts preferably closely approach but normally do not quite contact the outer layers of plywood.

In the alternative structures shown in Figs. 7, 8 and 9 the screen is imbedded in a thin layer of cork, such as that of Fig. 2, and placed between strips of the veneer which make up the plywood surface covering. As the screen does not come in direct contact with the plywood it will not weaken the latter by abrasion or cutting. This construction is shown more clearly in the enlarged view, Fig. 10, where, however, the strengthening screen and thin cork combination is used only in one of the two outer plywood coverings. The other covering layer in this instance is plain plywood.

20 In Figs. 11, 11A and 12, which show the preferred structure, the screen is located intermediate two arrays of mutually registering blocks 7 of cork. The posts 5 or 6 are inserted through some or all of these blocks and the intermediate screen.

25 When used in airplane wings, as shown in Figs. 13 and 14, the meeting edges of the folded structure are securely held in place by ends 8 which may be made up of two complimentary strips 9 and 10 of light weight material such as spruce glued together and held from lateral displacement by a single longitudinal round rod 11 of strong material such as birch Fig. 14. Where the aerofoil is of deep cross-section the complimentary strips 9 and 10 are provided with an additional longitudinal rod 11 of birch as shown in Fig. 13. This end section 8 is shaped to register with extensions 12 of the outer layer of plywood. Another rod 13 of birch is inserted between the edges of the wing and in abutment with the ends 8. All of these parts are held together by glue.

35 We claim:

1. A structural sheet comprising a layer of 45 particles of light weight cellular material compressed with a binder and having a wire mesh screen embedded therein, said layer having surface depressions, in combination with a layer of stiffening material attached to said first mentioned layer and overlapping said depressions.

2. A structural element comprising an inner 50 layer of light weight compressible material, outer layers of stiffening material, and an array of rigid posts extending transversely through said material with the ends thereof in close proximity to

but normally not in abutment contact with said stiffening layers, the said inner layer comprising blocks of the said compressible material spaced apart, each of said blocks enclosing one of said posts.

3. The element according to claim 2, wherein the said posts are of tubular formation.

4. The element according to claim 2, wherein the ends of the said posts are enlarged.

5. A structural sheet made up of adjoined layers, one of which comprises a plurality of blocks of compressible material spaced apart and collectively reinforced by a wire screen embedded in said blocks and extending into the spaces

therebetween, and another of which layers is plywood.

6. The element according to claim 5, together with an array of posts transversely piercing the said blocks and the said screen.

7. A structural element comprising an inner layer of compressed particles of light weight material and outer stiffening layers, one at least of said outer layers being made up of strips of veneer spaced apart and enclosing a wire mesh screen embedded in another layer of such material.
